UNITED STATES PATENT OFFICE.

HARLAN P. WALKER, OF McDONALD, PENNSYLVANIA.

ELEVATOR SLIDING DOOR.

1,234,090.

Specification of Letters Patent. Patented July 17, 1917.

Continuation of application Serial No. 838,306, filed May 13, 1914. This application filed November 7, 1916. Serial No. 129,940.

To all whom it may concern:

Be it known that I, HARLAN P. WALKER, a citizen of the United States, residing at McDonald, in the county of Washington 5 and State of Pennsylvania, have invented certain new and useful Improvements in Elevator Sliding Doors; and I do hereby declare the following to be a full, clear, and exact description of the invention, such as 10 will enable others skilled in the art to which it appertains to make and use the same.

This is a continuation of my prior application Number 838,306, filed May 13, 1914.

The invention relates to sliding doors, 15 which are positioned within elevator shafts, and the primary object of the invention is the provision of doors placed within the elevator shaft at each successive floor of the building in which the shaft is formed, which 20 doors normally divide the shaft into a plurality of compartments so as to prevent persons accidentally falling down the shaft, as well as materially decreasing the spreading of fire or the like in a building, in which 25 the draft usually occasioned within the elevator shaft would be eliminated by the provision of the sliding doors.

Another object of this invention is the provision of doors slideable laterally within the elevator shaft, the movement of which doors is controlled by the elevator car traveling within the shaft, so that the doors may be automatically opened or closed upon the approach or passage of the elevator car.

With the foregoing and other objects in view, this invention consists in such novel features of construction, combination, and arrangements of parts as will be hereinafter more fully described, illustrated in the accompanying drawings, and claimed.

In describing the invention in detail, reference will be had to the accompanying drawings, wherein like characters of references designate like or corresponding parts throughout the several views, and in which:

Figure 1 represents a side elevation of the invention partly broken away.

Fig. 2 is a bottom plan view of the doors, 50 and

Fig. 3 is a cross sectional view on the line 3—3 of Fig. 2.

Referring more particularly to the drawings, 1 designates respective floors of the building in which the elevator shaft 2 is located, which floors are provided with 55 openings 3 formed therein to permit of the passage of the elevator car therethrough. The elevator car 4 is provided with perpendicular side bars 5^a which have slotted engagement with the vertically extending guides 5, which are positioned upon both sides of the shaft as is ordinary in the construction of elevators of this type to guide it in its upward or downward movement 60 within the elevator shaft 2. Any suitable means for the propulsion of the elevator may be employed, this feature being in no way associated with the invention herein claimed. 70

The floors 1 of the building have guides 6 and 7 secured thereto, in which guides are slidably seated the doors 8 and 9, which doors are adapted to slide transversely within the elevator shaft 2 for forming an 75 obstruction to the shaft, or dividing the shaft into compartments in proportion with the floors of the building. The doors 8 and 9 have rollers 10 mounted upon stub-shafts 11, which rollers engage the guides 6 and 7 and decrease the friction occasioned by the sliding of the doors, providing means whereby the doors may be easily moved into or out of the elevator shaft. The doors 8 and 9 have links 12 and 13 pivotally connected to their opposite ends, which levers are in turn pivotally connected to levers 14 and 15 respectively. The levers 14 and 15 have their ends opposite to the ones which are pivotally connected to the levers 12 and 13, pivotally connected at 16 to a supporting bar 17, which bar is attached in any suitable manner to the construction of the elevator shaft (not shown). A pair of stops 17' is secured on the supporting bar 17 and arranged on opposite sides of each of the levers 14 and 15 for limiting the swinging movement of the latter in either direction. 80

The bars 14 and 15 have stub-shafts 18 mounted therein, substantially equidistant 90 from their ends, which stub-shafts extend inwardly toward the center of the elevator shaft and have rotatably mounted thereupon rollers 19, which rollers are adapted for pe- 95 100

peripheral engagement with the lever actuating members 20, carried by the elevator car 4.

The lever actuating members 20 are of U-shaped formation in cross section and are substantially frusto-triangular shaped, and have their apexes positioned farthermost from the top and bottom of the elevator car as is clearly shown in Fig. 1 of the drawings, 10 while their sides taper outwardly as they extend toward the top or bottom of the car. The lever actuating members 20 are positioned upon the extreme marginal edges of the sides of the elevator car, so that they 15 will pass between the ends of the doors 8 and 9, upon movement of the elevator, and engage the rollers 19, for forcing the levers 14 and 15 outwardly as is clearly shown in the upper section of Fig. 1 of the drawings, 20 which movement will in turn actuate the levers 12 and 13, and open the doors 8 and 9, so as to permit of the passage of the elevator car 4 through the openings 3 either upwardly or downwardly within the elevator shaft. The elevator car 4 has lever actuating 25 members 20 positioned upon both the top and bottom of the car so as to operate the levers either upon upward or downward movement of the car within the elevator shaft.

A bar 21 is carried by the elevator shaft structure, and is positioned directly below the bar 17. The bar 21 has connected thereto the ends of the coil springs 22 and 23, 25 which coil springs are connected to the levers 14 and 15 respectively, and exert a tension or pull upon the bars 14 and 15. This tension tends to keep the bars 14 and 15 in their innermost position when the doors 8 are in closed position to prevent rebounding of the doors, and to keep the bars 40 14 and 15 in their outermost position when the doors 8 are open, and to retain the doors 8 open until the elevator is passed, said 45 springs also hold the levers in either position so that the rollers 19 will always be in the path of the lever actuating member 20 upon movement of the elevator in either direction.

50 In the operation of the improved safety doors as above described, upon the upward movement of the elevator car 4 within the shaft, the lever actuating member 20 which is mounted upon the upper end of the car 55 will engage the rollers 19, and force the levers outwardly as is indicated by the arrow *a* in the lower section of Fig. 1 of the drawings, and this will position the levers as is shown in the upper portion of Fig. 1 60 of the drawings, opening the sliding doors 8 and 9, and permitting the elevator to pass therebetween. Upon downward movement 65 of the elevator car 4, the lever actuating members 20 will pass through the space 95 which is left between the ends of the doors 8

and 9 and the walls of the elevator shaft, and will engage the rollers 19, which will force the levers outwardly and open the doors, so as to permit of the passage of the cars therethrough.

70 From the foregoing description, taken in connection with the accompanying drawings, the advantages of the construction and of the method of operation of the improved elevator doors will be readily apparent to 75 those skilled in the art to which this invention appertains and, while in the foregoing, the principle of the operation of the invention has been described, together with the various features of construction, it is to be 80 understood that certain minor features of construction, combination and arrangement of parts may be altered to suit practical conditions, provided such alterations are comprehended within the scope of what is 85 claimed.

What is claimed is:—

1. The combination with an elevator car having a shaft therefor, a plurality of doors slideable transversely into said shaft, 90 a plurality of levers pivotally connected to said doors, and positioned for extending inwardly toward the center of the shaft and to one side thereof, and rollers carried by said levers, lever actuating members carried 95 by the elevator car for engaging said rollers for operating said levers for moving said doors outwardly upon the approach of the elevator car thereto, and inwardly upon the receding of the elevator car, and spring 100 means for preventing the rebounding of the doors in either open or closed position.

2. The combination with an elevator car having a shaft therefor, a plurality of doors slideable transversely into said shaft, a plurality of levers pivotally connected to said doors and positioned for extending inwardly toward the center of the shaft and to one side thereof, and rollers carried by said 105 levers, lever actuating members carried by the elevator car for engaging said rollers for operating said levers for moving said doors outwardly upon the approach of the elevator car thereto, and inwardly upon the receding of the elevator car, and contractile 110 springs secured to said levers and to the walls of the elevator shaft below said levers to prevent the rebounding of the doors in either opened or closed position.

3. The combination with an elevator car having a shaft therefor, a plurality of doors slideable transversely into said shaft, a link pivotally secured to the opposite ends of said doors adjacent each corner thereof, a lever pivotally secured to the side walls of the shaft and arranged below and adjacent to each one of the links, said levers having their free ends pivotally secured to the free ends of the links, rollers carried by said 125 levers adjacent the central portion thereof, 130

lever actuating members carried by the elevator car for engaging said rollers for operating said links and levers for moving said doors outwardly upon the approach of 5 the car thereto and inwardly upon the receding of the elevator car, and means for limiting the swing of the links and levers.

In testimony whereof I affix my signature in presence of two witnesses.

HARLAN P. WALKER.
